*Primary Examiner—Susan J. Lucas
Attorney, Agent, or Firm—Sheldon & Mak*[57] **CLAIM**

The ornamental design of a torchiere lamp with adjustable arm and adjustable lamp heads, as shown and described.

DESCRIPTION

FIG. 1 is a perspective view of the lamp of my invention; FIG. 2 is a right side view of the lamp in FIG. 1 with the side arm stretching out, with the side arm lamp head swivelled to an approximately horizontal position, and with the dish-shaped torchiere lamp head also swivelled to a horizontal position, and adjusted to a position furthest away from the side arm lamp head;

FIG. 3 is a rear view of the lamp in FIG. 2;

FIG. 4 is a left side view of the lamp in FIG. 2 with the side arm stretching out;

FIG. 5 is a front view of the lamp in FIG. 2; FIG. 6 is a top view of the lamp in FIG. 2; FIG. 7 is a bottom view of the lamp in FIG. 2; FIG. 8 is an enlarged view of the joint linking the side arm to the body of the lamp; FIG. 9 is a perspective view of an alternative embodiment of the lamp of my invention; FIG. 10 is a right side view of the lamp of FIG. 9, with the side arm stretching out, with the side arm lamp head swivelled to an approximately horizontal position, with the dish-shaped torchiere lamp head also swivelled to a horizontal position, and adjusted to a position furthest away from the side arm lamp head; FIG. 11 is a rear view of the lamp in FIG. 10; FIG. 12 is a left side view of the lamp in FIG. 10 with the side arm stretching out; FIG. 13 is a front view of the lamp in FIG. 10; FIG. 14 is a top view of the lamp in FIG. 10; FIG. 15 is a bottom view of the lamp in FIG. 10; FIG. 16 is a perspective view of a second alternative embodiment of the lamp of my invention; FIG. 17 is a right side view of the lamp of FIG. 16, with the side arm stretching out, with the side arm lamp head swivelled to an approximately horizontal position, with the dish-shaped torchiere lamp head also swivelled to a horizontal position, and adjusted to a position furthest away from the side arm lamp head; FIG. 18 is a rear view of the lamp in FIG. 17; FIG. 19 is a left side view of the lamp in FIG. 17 with the side arm stretching out; FIG. 20 is a front view of the lamp in FIG. 17; FIG. 21 is a top view of the lamp in FIG. 17; FIG. 22 is a bottom view of the lamp in FIG. 17; FIG. 23 is a perspective view of a third alternative embodiment of the lamp of my invention; FIG. 24 is a right side view of the lamp of FIG. 23, with the side arm stretching out, with the side arm lamp head swivelled to an approximately horizontal position, with the dish-shaped torchiere lamp head also swivelled to a horizontal position, and adjusted to a position furthest away from the side arm lamp head; FIG. 25 is a rear view of the lamp in FIG. 24; FIG. 26 is a left side view of the lamp in FIG. 24 with the side arm stretching out; FIG. 27 is a front view of the lamp in FIG. 24; FIG. 28 is a top view of the lamp in FIG. 24; and, FIG. 29 is a bottom view of the lamp in FIG. 24.
